UNITED STATES PATENT OFFICE.

JOHN F. SHOEMAKER, OF DES MOINES, IOWA, ASSIGNOR, BY MESNE ASSIGNMENTS, TO
J. T. GUERIN AND D. B. McDONALD, BOTH OF CHICAGO, ILLINOIS.

CHECK-CUTTER AND CHECK-BOOK HOLDER.

1,304,209.

Specification of Letters Patent. Patented May 20, 1919.

Application filed October 16, 1917. Serial No. 196,955.

To all whom it may concern:

Be it known that I, JOHN F. SHOEMAKER, a citizen of the United States, and resident of Des Moines, in the county of Polk and 5 State of Iowa, have invented a certain new and useful Check-Cutter and Check-Book Holder, of which the following is a specification.

The object of my invention is to provide a 10 check cutter and check book holder of simple, durable and inexpensive construction.

More particularly it is my object to provide a check cutter to be mounted on and used with the book holders of ordinary construction now in use, in such a way as to make it easy to place the cutter at the proper place for cutting the check from the stub along certain desired lines.

A further object is to provide such a device which can be readily and easily mounted on or detached from the check book, and which can be used with different kinds and sizes, and with checks of different sizes.

Still a further object is to provide a combination of such a cutter with a check and check book holder.

With these and other objects in view, my invention consists in the construction, arrangement and combination of the various 30 parts of the device, whereby the objects contemplated are attained, as hereinafter more fully set forth, pointed out in my claim, and illustrated in the accompanying drawings, in which:

35 Figure 1 shows a top or plan view of a check and check book holder equipped with a check cutter embodying my invention.

Fig. 2 shows a plan view of my improved check cutter laid out.

40 Fig. 3 shows a central, vertical, sectional view through the check cutter, and

Fig. 4 shows a vertical, sectional view of the check and check book, and check cutter shown in Fig. 1.

45 In the accompanying drawings, I have used the reference numeral 10 to indicate generally a check book holder or casing comprising the leather strip having the coacting snap fasteners 11 and 12 near its ends.

50 The check book holder 10 is provided near one end with a pocket 13, and near the other end with another pocket 14, for canceled checks or the like.

55 In connection with the check book I use a pad of checks 15 having between the stub

and body of the check a series of figures 16^a, which may be arranged as indicated in my patent issued May 8, 1917, Number 1,225,512. The checks may be fastened together by glue in the ordinary way or in any suitable manner and secured to the back of the checks is a stiff back 16 made of pasteboard or the like.

The pasteboard back 16 is slipped into the pocket 13. I provide a cutter, constructed 65 and mounted in the following manner.

The cutter comprises a flat plate 17 having a portion 18 at one end folded over the plate 17, as shown in Figs. 3 and 4.

At the opposite end of the plate 17 is a 70 downwardly opening channel 19 having at its edge opposite the plate 18 a horizontal portion 20 arranged on a level slightly lower than the plate 17.

Slidably mounted on the channel 19 is a 75 somewhat larger channel 21 having at one edge a horizontal extension or strip 22 slidably received between the member 18 and the plate 17, as shown in Figs. 3 and 4.

The channel 21 has at its other edge a flat 80 strip or extension 23, slidably mounted on the strip 20.

At the outer edge of the strip 23 is another flat strip 24 forming a cutter blade arranged substantially on a level with the 85 strip 20, as shown in Fig. 4.

At one end of the strip 24 is an upwardly extending handle or engaging member 25.

The plate 17 is secured to a supporting member which is preferably a substantially 90 rigid member or plate 26.

Secured to the strip 26 is a flexible member 27 forming a hinge and adjustable device. Secured to the flexible member 27 is a rigid member or strip 28 designed to be 95 slipped into the pocket 13 between the cover 10 and the stiff back 16, as illustrated in Fig. 4.

Many banks are putting out a leather check book holder of the general type shown 100 herein, having the pocket 13 or its equivalent receiving the stiff back on a pad of checks. It is my purpose to provide a cutter and supporting member therefor adapted to be used in connection with such check book 105 covers, and also adapted to be used with a check of the type shown in my patent herefore mentioned.

It is desirable that such a check cutter and support therefor should be so arranged 110

that the check cutter may be moved longitudinally of the checks and also transversely across the checks.

The use of the flexible member 27 permits 5 a longitudinal adjustment of the cutter on the checks and also permits some transverse adjustment.

The sliding mounting of the cutter blade 10 24 permits further and complete transverse adjustment of the cutter.

The advantages of such a construction as 15 is herein shown are largely seen from the foregoing description of the construction of my device.

15 It will be seen that the check cutter may be adjusted for cutting the checks along the desired lines, and that the check cutter and support therefor are so constructed and arranged that the device may be used with 20 the ordinary check book holders now commonly in use.

Some changes may be made in the construction and arrangement of the various

parts of my improved device without departing from the essential features and purposes thereof, and it is my intention to cover by my present application and the claim of the patent to be issued thereon, any modified forms of structure or use of mechanical equivalents which may be reasonably included within the scope of my claim. 25 30

I claim as my invention:

In a device of the class described, the combination of a check book cover having a pocket, a check cutter comprising a rigid member, a cutter blade adjustably mounted thereon, a flexible member operatively connected with said rigid member, and a rigid member operatively connected with said flexible member and adapted to be received within said pocket, whereby the cutter blade may be moved to a variety of positions with relation to the face of checks or the like in said cover. 35 40

Des Moines, Iowa, September 14, 1917.
JOHN F. SHOEMAKER.
